DISPLAY RACK FOR BOTTLES AND THE LIKE

Jay E. Tone III, 3811 Lincoln Place Drive,
Des Moines, Iowa

Filed Mar. 22, 1963, Ser. No. 74,086

Term of patent 14 years

(Cl. D80—9)

I claim:

The ornamental design for a display rack for bottles and the like, substantially as shown.
